COMBINED ELECTRIC GUITAR AMPLIFIER AND
LOUD SPEAKER HOUSING UNIT OR SIMILAR
ARTICLE

Charles A. Ross, 7th and S. Steuben,
Chanute, Kans. 66720

Filed June 3, 1966, Ser. No. 2,552

Term of patent 14 years

(Cl. D26—14)

Fig. 1.

Fig. 2.

Fig. 3.

Fig. 4.

FIG. 1 is a top, front perspective view of a combined electric guitar amplifier and loud speaker housing unit or similar article showing a preferred form of my new design wherein the top and side surfaces are fluted from front to back.

FIG. 2 is a side view thereof;

FIG. 3 is a back view thereof, the back being plain;

FIG. 4 is a bottom view thereof.

I claim:

The ornamental design for a combined electric guitar amplifier and loud speaker housing unit or similar article, as shown and described.
